N. P. B. ESKILDSEN,
WAGON BOX PROTECTOR,
APPLICATION FILED MAR. 9, 1910.

Patented Sept. 27, 1910.

UNITED STATES PATENT OFFICE.

NELS P. B. ESKILDSEN, OF HAMPTON, NEBRASKA.

WAGON-BOX PROTECTOR.

971,028.

Specification of Letters Patent. Patented Sept. 27, 1910.

Application filed March 9, 1910. Serial No. 548,245.

To all whom it may concern:

Be it known that I, NELS P. B. ESKILDSEN, a citizen of the United States, residing at Hampton, in the county of Hamilton and 5 State of Nebraska, have invented a new and Improved Wagon-Box Protector, of which the following is a specification.

My invention has for its object to provide a simple and inexpensive attachment for the 10 back end of lumber wagons, grain and other carts to protect the rear end, especially from the scoop shovel in unloading grain or other material from the wagon or cart.

In unloading wagons, especially those 15 from which the contents are removed by scoop shovels, the bottom of the box, particularly the outer end is always broken, by reason of the shovel catching and breaking pieces from between the meeting edges of 20 the floor boards.

My invention embodies a wagon bed protecting member having the peculiar construction and arrangement of parts, herein-after fully described, specifically pointed 25 out in the appended claims and illustrated in the drawings, in which:—

Figure 1, is a perspective view of the rear end of a wagon box with my invention applied, the end being broken away to the 30 more clearly illustrate the construction. Fig. 2, is a longitudinal section of the wagon box end. Fig. 3, is a perspective view of the attachment, in its complete form, for being attached to the wagon box. Fig. 4, 35 is a view of the blank sheet from which the protector is bent to shape.

In the drawing, I have shown so much of an ordinary form of wagon box as is necessary to illustrate the practical application 40 of my invention, it being understood my invention, with slight modifications of form on the showing made in the drawing, is applicable for substantially all types of wagons or carts from which the grain or other material is discharged by scooping the same 45 over the tail end of the wagon bed.

My protector comprises a sheet metal body which, in the blank form, has the shape 50 shown in Fig. 4, by reference to which it will be seen the same includes a transverse member that is cut at the opposite ends to form short lateral extensions or ears 1, the purpose of which will presently appear. The part 2 is of enough width to provide for 55 three bending lines designated x , y and z so as to provide, when the part 2 is bent on the

lines indicated, a protecting edge of a substantially U-shape in cross section, the lower member of which merges with a pendent flange b and the upper merges with a vertical flange or shoulder c that forms the abutment for the lower edge of the end gate and from which the inwardly projecting and inclined member d extends, it being understood the member d forms the wear plate 60 to be engaged by the scoop as it shovels out the contents of the box over the tail end thereof.

To sustain the protector edge proper and the pendent flange b in a rigid relation, the 70 ears 1 are bent down over the inner face of the outer opposite ends of the flanges b to which they are secured by the rivets e and for firmly securing the complete protector onto the wagon box the flange b has a number 75 of apertures f for the passage of the bolts g , that extend through the bolster or cross cleat h on the under side of the tail end of the wagon box, see Fig. 2.

From the foregoing, taken in connection 80 with the drawings the manner in which my protecting device is formed, its use in wagon boxes and the advantages thereof will be readily apparent.

By reason of the construction shown and 85 described, it can be easily made up into the desired sizes to fit different sizes of wagon beds and as the flange b is formed with a number of apertures, the protector can be 90 quickly bolted to the wagon box.

Having thus described my invention, what I claim and desire to secure by Letters 95 Patent, is:—

1. A wagon box end protector, comprising a substantially U-shaped sheet metal body 95 having a wear plate for projecting on the tail end of the wagon bed, a reinforced portion for fitting over the said end and a fastening member adapted for being secured to the wagon box. 100

2. A wagon box protector formed of a single piece of sheet metal bent to form a protecting portion of substantially U-shape in cross section and bent to form a pendent flange for fastening to the wagon box and bent to 105 form an inwardly extending wear plate for fitting over the tail end of the wagon bed.

3. The combination with the tail end of a wagon bed and a cross cleat on the under side thereof; of a metallic protector bent to 110 fit over the tail end of the wagon bed, provided with a pendent flange for engaging

with the cross cleat, an abutment for the lower edge of the end gate and an inwardly projected wear plate for covering the tail end of the wagon bed, and means for securing the flange to the said cleat.

4. The combination with the wagon bed; and a cross cleat on the under side of the tail end; of a metallic protector comprising a portion of a substantially U-shape in cross 10 section for fitting over the tail end of the bed, a flange that projects pendently from

the said portion, ears bent down from the upper part of the said portion over and secured to the flange, an abutment bent up from the inner edge of the top of the said portion and a wear plate that projects inwardly from the abutment. 15

NELS P. B. ESKILDSEN.
